US00D790517S

(12) **United States Design Patent** (10) Patent No.: **US D790,517 S**
(45) Date of Patent: ** Jun. 27, 2017

(54) **HOUSING FOR AN ELECTRONIC DEVICE**

(71) Applicant: **Apple Inc.**, Cupertino, CA (US)

(72) Inventors: **Jody Akana**, San Francisco, CA (US); **Bartley K. Andre**, Palo Alto, CA (US); **Shota Aoyagi**, San Francisco, CA (US); **Anthony Michael Ashcroft**, San Francisco, CA (US); **Jeremy Bataillou**, San Francisco, CA (US); **Brad G. Boozer**, Cupertino, CA (US); **Makiko Kawamura Brzezinski**, San Jose, CA (US); **Tyler Scott Bushnell**, Mountain View, CA (US); **Daniel J. Coster**, San Francisco, CA (US); **Daniele De Iuliis**, San Francisco, CA (US); **Colin Ely**, Cupertino, CA (US); **M. Evans Hankey**, San Francisco, CA (US); **Phillip M. Hobson**, Menlo Park, CA (US); **Julian Hoenig**, San Francisco, CA (US); **Richard P. Howarth**, San Francisco, CA (US); **Jonathan P. Ive**, San Francisco, CA (US); **Eric Steven Jol**, San Jose, CA (US); **Benjamin Jordan Kallman**, Menlo Park, CA (US); **Duncan Robert Kerr**, San Francisco, CA (US); **David Nazzaro**, Groveland, MA (US); **Trevor Jordan Ness**, San Francisco, CA (US); **Marc A. Newson**, London (GB); **David Pelletier**, Cupertino, CA (US); **Matthew Dean Rohrbach**, San Francisco, CA (US); **Fletcher Rothkopf**, Los Altos, CA (US); **Peter Russell-Clarke**, San Francisco, CA (US); **Jason Christopher Sauers**, Cupertino, CA (US); **Benjamin Andrew Shaffer**, San Jose, CA (US); **Anna-Katrina Shedletsky**, Mountain View, CA (US); **Mikael Silvanto**, San Francisco, CA (US); **Christopher J. Stringer**, Woodside, CA (US); **Samuel Bruce Weiss**, Los Altos Hills, CA (US); **Christopher M. Werner**, San Jose, CA

(US); **Eugene Antony Whang**, San Francisco, CA (US); **Michael Benjamin Wittenberg**, Sunnyvale, CA (US); **Stephen Paul Zadesky**, Portola Valley, CA (US); **Rico Zörkendörfer**, San Francisco, CA (US)

(73) Assignee: **Apple Inc.**, Cupertino, CA (US)

(**) Term: **15 Years**

(21) Appl. No.: **29/558,745**

(22) Filed: **Mar. 21, 2016**

Related U.S. Application Data

(63) Continuation of application No. 29/499,089, filed on Aug. 11, 2014, now Pat. No. Des. 752,044.

CLAIM

The ornamental design for a housing for an electronic device, as shown and described.

DESCRIPTION

FIG. 1 is a front perspective view of a housing for an electronic device showing the claimed design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines show portions of the design that form no part of the claim.
